Application June 16, 1950, Serial No. 10,556

Term of patent 14 years

(Cl. D48—20)

To all whom it may concern:

Be it known that we, Marl McMath and Robert C. Kling, citizens of the United States, residing at Newport, in the county of Campbell and State of Kentucky, have invented a new, original, and ornamental Design for a Keyhole Illuminating Device or the like, of which the following is a specification, reference being had to the accompanying drawing, forming part hereof, in which:

Fig. 1 is a top plan view of a keyhole illuminating device or the like, showing our new design.

Fig. 2 is a side elevational view of the device of Fig. 1.

Fig. 3 is an end view of the device of Fig. 1 taken from the left end thereof.

Fig. 4 is a cross sectional view taken on line 4—4 of Fig. 1.

We claim:

The ornamental design for a keyhole illuminating device or the like, as shown.

MARL McMATH.
ROBERT C. KLING.
